Inventor:
Robert E. Tabor,
By Hugh K. Wagner,
Attorney.

UNITED STATES PATENT OFFICE.

ROBERT E. TABOR, OF ST. LOUIS, MISSOURI, ASSIGNOR TO CINDERELLA HEEL CORPORATION, OF ST. LOUIS, MISSOURI, A CORPORATION OF MISSOURI.

HEEL.

1,409,615.

Specification of Letters Patent. Patented Mar. 14, 1922.

Application filed March 17, 1921. Serial No. 452,927.

To all whom it may concern:

Be it known that I, ROBERT E. TABOR, a citizen of the United States, residing at the city of St. Louis, in the State of Missouri, have invented certain new and useful Improvements in Heels, of which the following is a specification.

This invention consists in means for attaching the top lift or heel tread to the bottom part of the heel body or heel casting and constitutes an improvement over the invention that forms the subject-matter of the application of Harry G. Balthasar, 396,718.

In the accompanying drawings forming part of this specification, in which like numbers of reference denote like parts wherever they occur,

Figure 1 is a side elevation of a shoe heel, Figure 2 is a central vertical section thereof; and

Figure 3 is a top plan view of the attaching plate.

The heel casting 1 may be attached to the heel seat 2 in any desired manner. The heel casting 1 contains an upper cavity 3 and a lower cavity 4.

The partition 5 separates the cavities 3 and 4.

The holes 6 are drilled in and through the wall 7 of cavity 4 at an angle greater relatively to the vertical than in the said Balthasar device and are, furthermore, distinguished therefrom by being drilled entirely through the said wall 7, so as to communicate into the said cavity 4, whereas, in the other device they do not penetrate to the said cavity and are at such an angle that they merely enter the said wall 7, and are not drilled in such a direction as to point 40 toward the said cavity 4.

The prongs 8 borne by plate 9 are stamped out at a right angle to the said plate 9, and when their points 10 are entered into the holes 6 and a blow is struck, the said prongs 45 8 are forced into holes 6 and bent in the direction leading toward the cavity 4, and their points 10 bent by and along the floor of the cavity 4.

The rubber of top lift 11 may be attached 50 to plate 9 by vulcanization, in which event the plate 9 will be imbedded therein when molten, and the pads 12 will be formed on one side of holes 13 in plate 9, while the main body of the top lift 11 will be on the

other side thereof. If the top lift be of rubber, it may also be attached to plate 9 in any other desired manner. The same is true, also, if the top lift 11 be of leather or other material.

The particular feature of difference between this device and that of Balthasar, above named, are, that the prongs 8 are made longer; the holes 6 are drilled at a different angle from the similar holes in the Balthasar device; the said holes 6 are drilled so as to pierce wall 7 and into cavity 4, whereas, lengthening of the drill holes in the Balthasar device would not reach the similar cavity, but would only penetrate the wall further; and in this device the said lengthened prongs touch the floor of cavity 4 and are there bent in a clinching manner, the said bent points 10 touching the edge of each of their respective holes 6, and a clinch against pulling out from the said holes is 75 provided, resulting in a tighter hold of the said top lift to the said heel casting.

In addition to the said tighter attachment of the top lift to the said heel casting, just mentioned, other advantages inhere in this 80 construction, as follows: In case a cobbler is removing a top lift for substitution of another, and one of the prongs 10 happens to break off, it is not necessary for the cobbler to waste time minutely picking it out, 85 but he can simply place an awl in the drill hole 6 and drive the fragment out of it into cavity 4 and attach another top lift. Furthermore, it is possible with these longer prongs 10 and holes 6 slanted more nearly 90 to the horizontal, to repeat the changing of the top lifts more frequently. Aluminum is a soft metal, and with the holes 6 at the angle shown in the Balthasar device it might be possible to substitute top lifts only 95 about three times before such holes would lose their holding capacity on the short prongs that go therewith in the Balthasar device, while with the holes at a better angle in this present invention and with the longer 100 prongs therein shown and described, top lifts can be changed approximately a dozen times.

Having thus described this invention, I hereby reserve the benefit of all changes in 105 form, arrangement, order, or use of parts, as it is evident that many minor changes may be made therein without departing

from the spirit of this invention or the scope of the following claims.

I claim:

1. The combination of a heel having a cavity and passages opening into said cavity adjacent the floor of the same, and a plate having attaching means extended through said passages and terminating within said cavity, said attaching means being engaged 10 with the floor of the cavity and bent thereby, whereby the attaching means are securely held in position in the cavities and the passages.
2. The combination of a heel having a cavity and passages opening into said cavity adjacent the floor of the same, a plate having attaching means extended through said passages and terminating within said cavity, said attaching means being engaged with 15 the floor of the cavity and bent thereby, whereby the attaching means are securely held in position in the cavities and the passages, and a tread element carried by said plate.
- 25 3. The combination of a heel having a cavity and a wall surrounding the same and having drill holes passing through the said wall and opening into the said cavity, and

a top lift having an attaching plate bearing prongs adapted to pass through the 30 said drill holes into the said cavity, the said drill holes being arranged at such an angle as to afford a tight grip for the said prongs.

4. The combination of a heel having a cavity and a wall surrounding the same and 35 having drill holes passing through the said wall and opening into the said cavity, and a top lift having an attaching plate bearing prongs adapted to pass through the said drill holes into the said cavity, and there be bent 40 or clinched against the floor of the said cavity, the said drill holes being arranged at such an angle as to afford a tight grip for the said prongs.

5. The combination of a heel having a 45 cavity and passages opening out through one end of the heel and communicating with the said cavity and a plate having attaching prongs passing through the said passages and into the said cavity and the said 50 prongs being bent against the floor of the said cavity.

In testimony whereof I hereunto affix my signature.

ROBERT E. TABOR.
